UNITED STATES PATENT OFFICE.

EMANUEL ETTEHENIMER, OF NEW YORK, N. Y., ASSIGNOR TO THE AMERICAN STAMPING COMPANY, OF SAME PLACE.

DESIGN FOR AN ASH-CAN.

SPECIFICATION forming part of Design No. 26,041, dated September 15, 1896.

Application filed July 24, 1896. Serial No. 600,452. Term of patent 14 years.

To all whom it may concern:

Be it known that I, EMANUEL ETTEHENIMER, a citizen of the United States, residing in the city and county of New York, in the State of New York, have invented and produced a new and original Design for Ash-Cans, of which the following is a specification, reference being had to the accompanying drawings, in which—

10 Figure 1 is a plan view of a can, showing my design; and Fig. 2 is a side elevation of the same, these two views being deemed necessary to fully illustrate the design.

The leading feature of my design consists 15 in a series of ridges extending up and down on the exterior of the cylindrical surface of the can, such ridges being arranged in pairs or groups, like Gothic columns, each having a beveled end, so that the summit of the 20 ridge is shorter than its base, with a flat-bot-

tomed space between the members of each pair, so that the ridges stand distinct and independent. The ridges are rounded on their exteriors.

Referring to the figures, A is the main cylindrical surface of the ash-can, and B B one of the pairs of ridges. The rounded outer edge of each ridge is marked *b*. The clear flat-bottomed space between the ridges of each pair is marked C. At each side of each 25 pair of ridges on the cylindrical surface of the can are rounded projections or swells D.

What I claim is—

The design for an ash-can herein shown and described.

EMANUEL ETTEHENIMER.
